(57) **CLAIM**

I claim the ornamental design for a dispenser, as shown and described.

DESCRIPTION

FIG. 1 is a top perspective view, showing my new design for a dispenser;

FIG. 2 is a bottom perspective view;

FIG. 3 is a front elevation view thereof;

FIG. 4 is a rear elevation view thereof;

FIG. 5 is a left side elevation view thereof;

FIG. 6 is a right-side view thereof;

FIG. 7 is a top plan view thereof; and,

FIG. 8 is a bottom plan view thereof.
